UNITED STATES PATENT OFFICE.

HANS CLEMENT, OF NEW YORK, N. Y., ASSIGNOR TO GENERAL OPTICAL COMPANY, INC.,
A CORPORATION OF NEW YORK.

MACHINE FOR GRINDING COMPOUND LENSES.

1,260,872.

Specification of Letters Patent. Patented Mar. 26, 1918.

Application filed May 2, 1914. Serial No. 835,794.

To all whom it may concern:

Be it known that I, HANS CLEMENT, a citizen of the United States, residing at New York city, in the borough of Bronx and 5 State of New York, have invented certain new and useful Improvements in Machines for Grinding Compound Lenses, of which the following is a full, clear, and exact description.

10 This invention relates to machines for grinding cylindrical lenses. Lenses of this character are ground with tools having a surface which is the complement in curvature to the surface to be ground, the axis of 15 the surface of the tool being maintained in strict parallelism with the axis of the surface which is to be ground upon the lens blank.

The object of the invention is to provide 20 a machine of this character in which the supporting member for the lens blank or the tool is so constructed that the part which it supports moves in a curved path, the curvature of which approximates the curvature 25 of the surface to be ground on the lens blank, whereby the pressure exerted to hold the lens blank and tool in rubbing contact is not alone depended upon to cause these parts 30 to have relative motion in a path corresponding to the curvature of the surface to be ground.

Another object of the invention is to provide 35 a machine in which the sweep of the movable member is limited and the lens blank cannot, in its relative movement, with respect to the tool, be moved to a position in which it will be entirely disengaged from the grinding tool, for if this is permitted to occur, the edge of the lens blank frequently 40 becomes chipped or broken.

Another object of the invention is to provide 45 a machine in which the positions of the lens blank and tool may be interchanged whereby either convex or concave cylindrical lenses may be ground by substantially the same oscillatory movement of the movable parts of the machine.

With these and other objects in view the invention consists of the construction and 50 combinations which will be apparent to one skilled in the art from the detailed description hereinafter to follow and will be particularly pointed out in the appended claims.

In the accompanying drawings,

55 Figure 1 is a vertical sectional view

through a machine embodying the features of my invention;

Fig. 2 is a similar section taken at right angles to the view shown in Fig. 1; and

Fig. 3 is a detail showing the grinding 60 tool and lens blank in reverse position to that shown in the other views.

In the drawings, 1 and 2 respectively designate the lens blank and the grinding tool which are of the ordinary construction 65 used in machines of this character. The lens blank is cemented or otherwise secured to the surface of a rectangularly shaped lens block or holder 3 which is adapted to fit into a similarly shaped opening in a yoke 5 in 70 which it is secured in place by a set-screw 6, or in any other desired manner. The grinding tool 2 is provided with a lug 7 of a similar shape and size to the lens block, which lug is adapted to fit into a similarly 75 shaped recess in a tool holder 8 in which it is secured by a set-screw 9. The recess in the tool holder is centrally disposed in its top surface and arranged in axial alinement therewith is a sleeve 10 which is preferably 80 slightly tapered and is adapted to receive a spindle 12 carried by a spherical member or ball 13. The ball 13 is provided at its upper end adjacent the bottom of the spindle 12 with an annular groove forming a seat 85 for the lower end of the sleeve which is keyed to the spindle by means of a pin 15 projecting laterally from the lower end of the spindle, which pin engages in a slot formed in the bottom edge of the sleeve 10. 90 The spherical member or ball 13 is slightly flattened at its lower end and has a centrally disposed conically tapering recess therein arranged in axial alinement with the spindle 12. A rotating shaft 12' of any of the well 95 known forms of hand-surfacing machines at present used, fits into the recess and rotates the tool holder and tool, (see Fig. 2).

The spherical member or ball 13 constitutes the male member of a ball and socket 100 joint, the female member of which is made in two parts 16 and 17, respectively, which are united by means of screws 18 passing through abutting lugs 19. Mounted on the top annular surface of the two parts 16 and 105 17, is a ring 18' which is secured thereto by screws or pins 19'. The ring 18' has its inner wall beveled, as shown, which abuts against the outer surface of the sleeve 10 and thus serves as a stop to limit the path of the 110

oscillatory movement of the parts 16 and 17 relative to the tool holder and grinding tool, and therefore maintains the lens blank, which is mounted on the parts 16 and 17, as 5 will be hereinafter set forth, in engagement with the grinding tool. This is important, for since the lens blank is always maintained in engagement with the grinding tool, the parts remain in operative relation and the 10 edge of the lens blank cannot be chipped or broken, which otherwise frequently occurs when the edge of the blank strikes the edge of the grinding tool as they pass out of engagement. The tool holder 8 is provided 15 with a hood 20 which serves as a dust cap to protect the upper open part of the ball and socket joint from the emery and glass particles which would otherwise soon clog the joint during the grinding operation.

20 Projecting laterally from the parts 16 and 17, are curved arms 20 and 21, which have vertically disposed ends to which are secured two pairs of guide-rods 23 and 24, the arms 20 and 21 being preferably grooved or 25 slotted as at 23' at diametrically opposed points, into which grooves the lower ends of the rods are secured by screws or in any other desired way in order to obtain a substantially rigid connection. Projecting laterally from the yoke 5 are arms 25, the lower 30 ends of which are bent slightly downwardly and are adapted to fit between the upper ends of the spaced guide-rods 23 and 24, the rods of each pair being spaced just a sufficient distance apart to permit the arms 25 to 35 slide freely up and down therebetween but to prevent any lateral movement of the same. The arms 25 are preferably circular in cross section and arranged on them adjacent their free ends and spaced apart a distance equal 40 to the distance between the two pairs of guide-rods 23 and 24, are disk-like members 26, the outer surfaces of which are adapted to abut the inner side faces of the guide-rods 23 and 24 and are of spherical curvature, the radius of which is equal to one-half 45 the distance between the rods, so that arms 25 may be tilted within the guide-rods and a portion of the curved surfaces of the disks 50 will remain in engagement with the side faces of the rods. By spacing each pair of guide-rods 23 and 24 apart just sufficient to permit the arms 25 to slide vertically up and down thereon in a determined plane and by 55 providing the disks 26, any free independent movement of the yoke 5 and lens holder 3 with respect to its support, except in a fixed plane is prevented, as will be hereinafter referred to. The center of the ball and 60 socket joint is preferably chosen so that the radial distance from the center of the ball and socket joint to the surface of the grinding tool is equal to the radius of curvature of a lens of the average cylindrical power for which the machine is designed, so that

there will be practically little or no relative movement of the arms 25 within the guide rods 23 and 24 in the grinding of a lens of a normal size.

Trunnion pins 28 are fitted into alining 70 grooves formed in the abutting surfaces of the parts 16 and 17, and the ends of these pins pass into elongated vertical slots 29 cut in the spherical surface of the ball 13, which slots are of sufficient length to permit the 75 parts 16 and 17 to rock on the ball 13 in a vertical plane passing through the pins, until the ring 18' abuts against the sleeve 10. The pins 28 connect the supporting structures of the lens blank and tool holder together for synchronous rotation. The surface of the grinding tool is so ground that when positioned in the tool holder 7 its fixed diametral line or axis is preferably 80 parallel to the alining longitudinal axes of 85 the pins 28, but the fixed axis of the tool may be arranged at right angles to the axis of the pins, if desired. By the construction described, the axis of the tool and of the lens blank are maintained in strict parallelism 90 with each other, irrespective of the direction of the path of movement of the lens blank across the face of the grinding tool, which path of movement is changing constantly since the tool and lens blank are 95 constantly rotating and the oscillatory movement, which is imparted to the lens blank in the construction shown, is given by hand or by machinery and takes place in a comparatively fixed plane, as will be later described. 100

The lens block 3 is provided with a conically shaped recess 30 into which is adapted to fit any member such as a reciprocating rod 30' through which the lens blank is given its oscillatory movement and the 105 pressure necessary for the grinding action is exerted upon it. This member may be operated either manually or automatically in accordance with any of the well known forms of hand surfacing machines now on 110 the market.

The operation of the machine is as follows:—Rotation is imparted to the entire machine by means of the rotating shaft 12' which fits into the ball 13. The surface of 115 the grinding tool is covered with the necessary abradant material such as emery or the like, and the lens blank which has been roughed to approximately the curvature of the grinding tool, and cemented to 120 the lens block 3, is secured in the yoke 5, which is then placed between the upper ends of the guide-rods 23 and 24. During the rotation of the machine, the lens blank is oscillated in a fixed plane by means of the 125 reciprocating arm 30' and by which the necessary pressure is exerted upon the lens blank for obtaining the grinding action. As the tool and lens blank rotate in synchronism, since the oscillatory movement 130

- is imparted to the lens blank in practically a fixed plane, the direction of this path of movement of the lens blank across the face of the grinding tool is continually changing.
- 5 The pin and slot connection, however, between the portions of the ball and socket joint prevents any rotary movement of the lens blank and grinding tool in a horizontal plane so that the fixed axis of the lens and tool are always maintained in strict parallelism with each other. Since the ball and socket joint is arranged so that its distance from the surface of the grinding tool is equal to the radius of the desired cylindrical power of the lens or closely approximates it, the curvature of the oscillatory paths closely conforms to the surface curvature of the grinding tool of the lens blank and pressure which is exerted upon the lens
- 10 blanks will be substantially uniform and normal to the entire surface in contact with the surface of the grinding tool. The arms of the yoke will therefore have a minimum sliding movement within the guide rods 23 and 24, which will result in an accurate grinding of the lens, since the pressure with which the lens is brought into contact with the grinding tool is only depended upon to maintain these parts in correct rotary contact.
- 15 When grinding lenses of the cylindrical powers, which are of a greater or less radius than the distance from the surface of the grinding tool to the center of the grinding tool, the arms 25 are free to slide in the guide-rods 23 and 24, and the lens blank is therefore free to follow the curvature of the surface of the grinding tool, but as the difference in curvature in the lenses is slight, this free movement of the lens blank independently of its supporting structure will practically be negligible and the pressure on the lens blank will remain substantially normal to the surface of the grinding tool at the points of rubbing contact between it and the lens blank. However, since arms 25 are prevented from lateral displacement and are constrained to move in a plane determined by the position of the guide-rods 23 and 24, this free movement cannot throw the fixed line or axis on the blank and tool out of absolute parallelism, and the resulting surface ground on the lens blank will have its axis accurately determined. The beveled surface of the ring 18' will also prevent the lens blanks from being moved in oscillatory paths of sufficient length to prevent the lens blank from entirely passing out of engagement with the surface of the tool and will therefore prevent the edges of the lenses from being broken or chipped, which frequently occurs when this happens.
- 20 In the modified construction shown in Fig. 3, the positions of the lens blank 1' and grinding tool 2' are reversed or inter-
- changed, which is a more desirable assembly for grinding convex lenses for, as will be readily seen from the drawing, by interchanging the blank and tool in this manner, the oscillatory movement of the supporting structure will again closely conform to the path in which the grinding tool must move in order to grind the convex lens and therefore the free movement of the yoke 5 and the arms 25 with respect to rods 23 and 24, is reduced to a minimum, which will necessarily result in the obtaining of a more accurately ground lens. This is an important feature of my invention as it permits both concave and convex lenses to be ground on the same machine while the parts of the machine are actuated in substantially the same manner resulting in obtaining more perfectly ground lenses.
- 25 I claim:
1. In a lens grinding machine, two holders one adapted to support a lens blank and the other to carry a grinding tool, a frame having a universal joint connection with one of said holders, means for loosely mounting the other of said holders in said frame for movement in a fixed plane, and means for preventing relative movement between said frame and its holder in a fixed plane.
- 30 2. In a lens grinding machine of the character described, two holders one for a lens blank and the other for a grinding tool, a yoke having laterally extending arms secured to one of said holders, a support for said yoke into which the ends of said arms fit, a support for the other holder, a ball and socket joint between said supports, and means for preventing relative rotation of the supports in a fixed plane.
- 35 3. In a lens grinding machine of the character described, two holders one for a lens blank and the other for a grinding tool, a support for one of said holders permitting free movement of said holder in a determined plane, a support for the other of said holders and a universal joint connection between said supports, and means for preventing relative rotary movement of said supports in a fixed plane.
- 40 4. In a lens grinding machine of the character described, two holders one for a lens blank and the other for a grinding tool, a support for one of said holders in which said holder is freely mounted for movement in a determined plane, a support for the other of said holders in which said holder is rigidly mounted, means including a universal joint connection for connecting said supports, and means for preventing relative rotary movement of said supports in a fixed plane.
- 45 5. In a machine of the character described, two holders one for a lens blank and the other for a grinding tool, a yoke

rigidly secured to one of said holders having laterally extending arms, a support for said yoke comprising bifurcated arms into which the ends of said laterally extending arms of said yoke fit, a support for the other of said holders, and a ball and socket joint connection between said supports.

6. In a lens grinding machine of the character described, a holder for a lens blank or 10 a grinding tool, a yoke adapted to be rigidly secured to said holder, said yoke having arms extending laterally therefrom, a support for said yoke comprising bifurcated arms into which the ends of said arms slid- 15 ingly fit, and means for preventing movement of said yoke in a direction parallel to its longitudinal axis.

7. In a lens grinding machine of the character described, a holder for a lens blank or 20 a grinding tool, a yoke adapted to be rigidly secured to said holder, said yoke having arms extending laterally therefrom, a sup-

port having bifurcated guide-arms between which the ends of said yoke arms slidingly fit, and members on said yoke arms for preventing movement of said yoke in a direction parallel to its longitudinal axis.

25

8. In a grinding machine of the character described, a holder for a lens blank or 30 a grinding tool, a yoke adapted to be rigidly secured to said holder, said yoke having arms extending laterally therefrom, a support for said yoke comprising guide-arms between which said yoke arms slidingly fit, and disk-members on said yoke arms having 35 curved surfaces abutting said guide-arms for preventing movement of said yoke in a direction parallel to its longitudinal axis.

35

In witness whereof, I subscribe my signature, in the presence of two witnesses.

HANS CLEMENT.
